UNITED STATES PATENT OFFICE

146,931

DESIGN FOR A VEHICLE

Arthur A. Turton, Los Angeles, Calif.

Application October 20, 1945, Serial No. 123,058

Term of patent 14 years

(Cl. D14—3)

To all whom it may concern:

Be it known that I, Arthur A. Turton, a citizen of the United States, residing at Los Angeles, in the county of Los Angeles and State of California, have invented a new, original, and ornamental Design for a Vehicle, of which the following is a specification, reference being had to the accompanying drawing, forming a part thereof.

Figure 1 is a plan view of a vehicle showing my new design.

Figure 2 is a side elevational view of the design shown in Figure 1.

Figure 3 is a front elevational view of the design shown in Figure 1.

Figure 4 is a top perspective view of the design shown in Figure 1 as seen from a point somewhat to the rear thereof.

The side of the vehicle opposite that shown in Figure 2 is the same as that shown in said figure.

I claim:

The ornamental design for a vehicle, substantially as shown and described.

ARTHUR A. TURTON.
